(57)

CLAIM

The ornamental design for a drifting kart, as shown and described.

DESCRIPTION

FIG. 1 is a top, front, left-side perspective view of a drifting kart of our design;

FIG. 2 is a bottom, front, right-side perspective view thereof;

FIG. 3 is a front elevation view thereof;

FIG. 4 is a rear elevation view thereof;

FIG. 5 is a right-side elevation view thereof;

FIG. 6 is a left-side elevation view thereof;

FIG. 7 is a top plan view thereof; and,

FIG. 8 is a bottom plan view thereof.

The dash-dot broken lines immediately represent the bounds of the claim and all other broken lines represent portions of the article that form no part of the claimed design. None of the broken lines form a part of the claim.

1 Claim, 7 Drawing Sheets
